AUTOMATIC TIME PROGRAM SELECTOR
FOR RADIO RECEIVING SETS

Frank Gustave Siegel, Oakland, Calif.

Application August 25, 1933, Serial No. 686,769

2 Claims. (Cl. 250—20)

This invention relates to improvements in program selectors for radio receiving sets, and an object of the invention is to provide an apparatus that can be connected up to a radio set and which will operate to change the setting of the dial of the radio receiving set so as to tune it in on one station and then on another, each at a predetermined time, which stations have been selected in advance to prepare a fixed program for a given number of hours.

A still further object of the invention is to provide an improved dial for an apparatus of the kind above suggested.

A still further object of the invention is to improve generally upon automatic station or program selectors as now generally known and used.

Other objects and advantages of the invention will become apparent from a study of the following description taken in connection with the accompanying drawings wherein:

Figure 1 is a front elevational view of a program selector embodying the features of the present invention.

Figure 2 is a top plan view thereof.

Figure 3 is a sectional view taken substantially on the line 3—3 of Figure 1.

Figure 4 is a fragmentary detail sectional view through an arm forming part of the invention.

Figure 5 is a plan view of a portion of a modified form of dial.

Figure 6 is a perspective view of an end portion of one of the segments used in the building up of the dial suggested in Figure 5 and

Figure 7 is a fragmentary detail sectional view showing the manner of securing the dial sectors to the hub of the dial.

Referring to the drawings by reference numerals it will be seen that the device comprises a suitable base or platform 10 on which is suitably mounted a bearing bracket structure 11 that supports one end portion of the shaft 12 provided for the tuning dial of the radio set. Also mounted on the bracket 11 is a shaft 14 provided with a gear 15 that meshes with a gear 16 provided on the shaft 12, and through the medium of this gearing the shaft 14 rotates the shaft 12 and shifts the dial on the radio set.

Mounted at one end of the base plate 10 is a suitable electric clock 17, the works of which include an arbor shaft 18 having thereon a worm 19 that is in mesh with a worm wheel 20 mounted on a vertical shaft journalled in a suitable bracket 21. The vertical shaft, indicated by the reference numeral 22 is connected by gearing 23 with a horizontal shaft 24 that is journalled in suitable sup-

porting brackets 25. On one end of the shaft is secured a control dial either of the type shown in Figure 1 and indicated generally by the reference numeral 27, or of the type indicated generally by the reference numeral 28 and suggested in Figures 5 to 7 inclusive.

The dial 27 is in the form of a circular card or disk which is clamped in place by a screw 29 having a head 30.

On the dial 27 are marked concentric circular lines 31 designating wave lengths in meters or kilocycles and a series of radial longitudinally curved lines 32 fifteen degrees apart as divisions of time during which such wave lengths are intended to be employed. Each line will represent a point of time fifteen minutes later than the preceding line and any four consecutive spaces will represent one hour. In the present instance the arrangement is such that the total number of lines with the spaces between them will represent twenty four hours, and on the periphery of the disk, at every fourth line will be, as shown, a suitable numeral for indicating the hour represented by that particular line.

It will be understood that when the dial such as indicated by the reference numeral 27 is used the program will be first charted thereon, and the disk is then cut along the line thus made on the disk in the preparation of the program, so that the dial, when ready for use will have an edge contour somewhat akin to that suggested in Figure 1 presenting periodically variant surfaces or steps of varying depth and length, it being apparent that the cutting will follow along a plurality of the division lines 32 and the wave length indicating lines 31.

It will be understood that the dial is rotated continuously by the clockworks 17, and means are provided for cooperation with the dial 27 to operate the tuning dial of the radio set so as to tune the set in on one station and then on another each at a predetermined time, which station as before suggested will have been selected in advance and the chart delineated and cut to make up the fixed program for a desired number of hours.

The means above mentioned consists in the present instance of an arm 33 that is tapered, and adjacent its smallest end has extending laterally therefrom a shaft 34 on one end of which is a roller 35 that is in proper wiping engagement with the edge of the dial.

At its largest end the arm 33 is mounted on one end of a suitably mounted shaft 36. At the last named end the arm 33 has fixed thereto

a gear segment 37 that is in mesh with a pinion 38 provided on the aforementioned shaft 14 for transmitting movement of the arm 33 to the shaft 14, and from the shaft 14, through the gearing 15, 16 to the radio tuning dial shaft 12 for setting the tuning dial of the radio set.

For raising the arm 33, that is to say for swinging the arm in a clockwise direction (Figure 1) there is provided an electric motor 39 that has 10 its armature shaft equipped with a gear 40 that is in mesh with a gear 41 provided on a suitably mounted shaft 42. On the shaft 42 there is also provided a pinion gear 43 that is in mesh with a suitably mounted idler gear 44, which latter, is 15 in mesh with a relatively large gear 45 secured on the shaft 36.

For controlling the circuit to the motor 39 there is mounted a switch which includes a fixed contact member 46 mounted on a block 47 of insulating material suitably secured to the arm 33. Cooperable with the contact 46 is a movable contact 48 secured to a block of insulating material 49 provided on the free end of the shaft 34.

The shaft 34 has an intermediate portion thereof mounted in a slide 50 that operates in a longitudinal slot 51 provided in the free end of the arm 33 and is normally urged inwardly toward one end of the slot 51 through the medium of an adjustable spring device 52. It will thus be seen 25 that when the block 50 is caused to move to the left in Figure 4 due to the action of the revolving dial on the roller 35 the contact 48 will move into engagement with the contact 46 thus closing the circuit to the motor 39, and this motor 30 through the medium of the gearing 40, 41, 43, 44 and 45 will rotate the shaft 46 for swinging the arm 33 in a clockwise direction. At the same 35 time the movement of the arm 33 will, through the medium of the gearing 37, 38, 15 and 16, be transmitted to the shaft 12 of the tuning dial of the radio receiving set to properly set the dial for tuning in on the proper station.

The arm 33 is normally urged to rotate in a counter-clockwise direction through the medium 45 of weights 53 suspended from the free end of the arm 33 through the medium of a suspension member 54. The utility and operation of the device will be apparent from the following:

Assuming that the program as selected is to 50 commence at one o'clock and continue through to eight o'clock P. M. as suggested on the dial in Figure 1. The roller 35 is placed into engagement with the peripheral edge of the dial 27, let us say, in line with the sector line indicating twelve noon. 55 It will be understood that the dial 27 runs continuously and in the direction indicated by the arrow in Figure 1. As the dial 27 rotates the roller 35 engaging the edge of the disk will control the swinging of the arm 33 as the roller 60 moves into and out of the notches formed by cutting the disk in preparing the same according to the stations selected in making up the program. Thus generally it will be seen that during the period of time in which the roller 35 65 is operating within a notch the radio set will be tuned in on a particular station, and as the roller moves from one notch to the other the tuning dial of the radio receiving set will be automatically turned for cutting out one station and tuning in on the next succeeding station, and 70 that further this changing from one station to the other will continue in chronological order and at predetermined varying intervals of time until the selected program has been completed.

75 It will be further apparent that as the roller

35 moves in to a notch the arm 33 will swing in a counter-clockwise direction and inwardly toward the center of the dial, and that this movement of the arm 33 will be transmitted through the gearing hereinbefore described to the shaft 12 of the tuning dial of the radio receiving set thus setting the dial in the desired position for tuning in on the proper station.

As the dial 27 turns through the angle between the lines 32 defining the width of the particular 10 notch in which the roller 35 is operating the tuning dial of the radio receiving set will of course remain in set position.

To swing the arm 33 in a clockwise direction it will be apparent that the motor 39 will be 15 brought into operation in the following manner: When the dial 27 has moved through the angle above indicated the edge of the dial defining one side of the notch in which the roller 35 is operating moves into engagement with the roller, and 20 the rotation of the dial will cause the roller 35, shaft 34 and associated parts to move toward the smallest end of the arm 33. This will result in a movement of the contact 48 into electrical engagement with the fixed contact 46 thus closing 25 the circuit to the motor 39. From the motor 39 power is transmitted through the gearing hereinbefore set out to the shaft 36 for rotating the shaft in a clockwise direction which shaft having the arm 33 thereon will cause said arm to swing 30 in a corresponding direction. The swinging of the arm in this direction will be transmitted to the gearing 37, 38, 15 and 16 to the shaft 12 to turn the dial of the radio receiving set for tuning in on the desired station.

The dial 28 shown in Figures 5 to 7 inclusive will be used in substantially the same manner as the dial 27, but instead of being constructed from a single disk is made up of a series of segments, including the larger segments 55, three quarter 40 hour segments 56, quarter hour segments 57, and half-hour segments of varying length, the outer edges thereof serving in the same manner as the lines 31 on the dial 27. The dial 28 also includes a central hub member 58 provided with a peripheral flange 59 provided with inner and outer series of sockets 60 and with which apertures 61 on the inner end of sectors 55, 56, and 57 align to accommodate retaining pins 62. There are, in the present instance two series of pins 62 for each of the 50 sectors. The sectors, as clearly shown in Figure 7 are confined on the hub between the flange 59 and an annular retaining disk or washer 63 that fits on the hub as shown in Figure 7. When the dial 28 is thus assembled the hub 58 thereof is 55 secured on the end of the shaft 24 and can be used in substantially the same manner as the dial 27.

I claim:

1. The combination of a radio receiving set 60 having a shaft for the tuning dial, a device for rotating the shaft for automatically setting the tuning dial, said device comprising a program dial mounted to rotate and divided into sectors of varying lengths and arcs presenting for the dial 65 a peripheral edge having a substantially periodically variant surface, an arm mounted to oscillate across the face of the program dial, and said arm being weighted at one end to rotate in a counter-clockwise direction, a driving connection 70 between the other end of said arm and the shaft for the radio tuning dial for transmitting movement of the arm to said tuning dial shaft, a slide on the weighted end of said arm, lateral means carried by the slide and in wiping engagement 75

with the said surface of the program dial for shifting the slide, a motor having driving connection with said other end of the arm for rotating the latter in a clockwise direction, said motor including a circuit, a fixed circuit contact on the arm, a circuit contact on the slide for wiping engagement with the first named contact upon movement on the slide in one direction for closing the circuit to the motor at predetermined intervals and time means for continuously rotating the program dial.

2. Means for controlling a radio receiving set, comprising a shaft connected with the tuning element of the receiver, an arm for connection with said shaft, and mounted for swinging movement, a program dial mounted to rotate, and divided into a plurality of sectors of varying lengths and arcs presenting a peripheral edge for the program dial having a periodically variant surface comprising notches of varying depth and

widths, a motor having driving engagement with said arm to cause the latter to swing in one direction, a slide on said arm, a shaft extending through the slide and having roller means on one end arranged in wiping engagement with said surface of the program dial, a circuit for said motor, and circuit closing means connected with said arm and slide respectively to close the motor circuit upon movement of the slide in one direction and start the motor and move said arm in one direction to set the dial of the radio set in a desired position; said roller means being adapted to pass alternately into and out of succeeding notches in a manner to cause the tuning dial of the radio set to rotate through a predetermined angle upon movement of the roller from one notch to the other, and means for continuously rotating the program dial.

FRANK GUSTAVE SIEGEL. 20
